HYDROCARBON REACTION

William H. Shiffner, San Francisco, and Laverne P. Elliott, Berkeley, Calif., assignors to Standard Oil Company of California, San Francisco, Calif., a corporation of Delaware

Application August 30, 1939, Serial No. 292,678

1 Claim. (Cl. 260—683.4)

This invention pertains to the manufacture of high antiknock motor fuel hydrocarbons from relatively light paraffin hydrocarbons boiling below the range of the usual liquid fuels and, more particularly, to the utilization of relatively light paraffinic hydrocarbons having from three to five carbon atoms per molecule, and especially the normal paraffin hydrocarbons of this group, to produce high antiknock motor fuel hydrocarbons therefrom.

In the cracking of hydrocarbon oils normally gaseous hydrocarbons are produced which are lighter than gasoline and too volatile to be included therein in more than minor quantities and which for a number of years were therefore regarded as waste products from the cracking operation. More recently, however, processes have been devised for the utilization of some of the components of such cracking gases in the manufacture of motor fuel, but the utilization of the paraffinic components, such as butanes, pentanes and propane, and especially the normal paraffins, in the manufacture of high antiknock motor fuel has met with but little success. On pyrolysis at high temperatures they produce an aromatic rich naphtha but in yields that are quite uneconomical. Thermal processes combining dehydrogenation and polymerization have been productive of better yields of liquid boiling in the motor fuel range but of inferior quality in certain respects and particularly in antiknock quality when used in motors operating at the high temperatures desirable in aviation service. Catalytic dehydrogenation followed by catalytic polymerization and hydrogenation of the polymers is susceptible of producing desirable liquid hydrocarbon fuel components but in yields that are still well below the theoretical maximum, based on the light paraffin consumed.

An object of the present invention is therefore to provide a process whereby the paraffin hydrocarbons containing from three to five carbon atoms per molecule can be converted, with substantially theoretical yield, to liquid hydrocarbons having a high antiknock value and suitable in other respects for use as or in the preparation of aviation motor fuels.

Another object of our invention is to provide a process wherein catalytic dehydrogenation, polymerization, hydrogenation and alkylation reactions are so combined, positioned and interrelated as to convert the light paraffin hydrocarbons containing less than six but more than two carbon atoms per molecule, such as produced during the cracking or reforming of petroleum

oils or during the stabilization of natural gasoline, into liquid hydrocarbons of high antiknock value with yields approximating the theoretical and a minimum of operating difficulty.

5 Other important objects of the invention will be apparent from the following description and the appended claim.

This invention contemplates a process for the substantially complete utilization of such paraffins as butanes, pentanes and propane for the manufacture of high antiknock motor fuel hydrocarbons, and especially for the manufacture of high antiknock motor fuel hydrocarbons suitable for use in or as aviation gasoline, and while it 10 will be described and discussed with particular reference to the utilization of butanes it is not intended to be limited thereto.

In accordance with the invention a light paraffinic hydrocarbon, such as normal butane or a mixture of normal and isobutane, is catalytically dehydrogenated in a dehydrogenating zone to produce the corresponding olefin or olefins and the olefins produced are catalytically polymerized in a polymerization zone to produce olefin polymers which, when hydrogenated, are suitable as components in high antiknock motor fuel. The equilibrium conditions are, however, such that it is usually not practical to operate a commercial dehydrogenation plant under conditions to 15 convert more than a minor fraction, seldom more than 25 to 30%, of a paraffin to the corresponding olefin in a single operation and, therefore, the hydrocarbons leaving the dehydrogenator will contain a substantial proportion of the original paraffin in admixture with the olefins produced. Also, when such a mixture of olefin and unconverted paraffin is passed through a catalytic polymerization plant to polymerize the olefin, it is impractical, even with recycle operation, 20 to obtain better than 85 to 90% conversion of the olefin to polymers and, therefore, the hydrocarbon mixture leaving the polymerization zone contains both unreacted paraffin and some unpolymerized olefin.

25 If this unreacted paraffin is returned to the dehydrogenation plant, as must of course be done if a substantial portion of the original paraffin is to be converted to liquid motor fuel, the unpolymerized olefin admixed with it may be consumed to a substantial extent in side reactions, the products of which comprise hydrocarbons of one or two carbon atoms and of relatively low value together with traces of gummy or tar-like material that may be deposited in the dehydrogenation 30 catalyst and very materially reduce its effective

life period between regenerations. It is easily seen from the above figures that at least 10% of the paraffin processed might be lost in this way and that the operation of the process would also be materially complicated by the necessity of frequent catalyst regeneration.

It is a significant feature of this invention that the mixture of unreacted hydrocarbons comprising unreacted paraffin and unpolymerized olefin leaving the polymerization stage is passed to an alkylating zone wherein the olefin is removed through alkylation of an isoparaffin prior to returning the unreacted paraffin to the dehydrogenation step. The alkylation reaction is effective to remove substantially all of this olefin, in the production of valuable alkylers, and the unreacted paraffin is thus left substantially free of any olefin, and the olefin-free unreacted paraffin is then recycled to the dehydrogenation zone. This is especially desirable, since the recycle of even a small proportion of olefin to the dehydrogenation zone is objectionable because of the loss of raw material occasioned, the adverse effect on the equilibrium in the dehydrogenation reaction in the dehydrogenation zone and the tendency to cracking, further dehydrogenation, tar production and catalyst poisoning, as above pointed out.

The olefin polymers boiling in the gasoline range have a high antiknock value when used in motors operating at the relatively mild temperatures encountered in ordinary automotive service but lose this value to a very considerable extent when employed in fuels for aviation use at higher engine temperatures. The polymers when hydrogenated may, however, be satisfactorily used in aviation fuels and it is accordingly contemplated by the present invention that the hydrogen produced in the paraffin dehydrogenation step may be employed for hydrogenation of the olefin polymers produced in the polymerization step thereby giving a product of greater value from the same ultimate raw material.

The process of the present invention thus includes a catalytic dehydrogenation step in which a light paraffin hydrocarbon is catalytically dehydrogenated with the production of the corresponding olefin and free gaseous hydrogen, a catalytic polymerization step in which a portion of the olefins so produced are catalytically polymerized to olefin polymers boiling substantially in the range of aviation motor fuel, a hydrogenation step in which these olefin polymers are catalytically hydrogenated by the hydrogen produced in the paraffin dehydrogenation step and an alkylation step in which olefins remaining unpolymerized in the polymerization step are caused to alkylate an isoparaffin prior to returning the originally undehydrogenated paraffin, with which they are mixed, to the dehydrogenation step. By this combination of steps a process results which is complete and effective for the conversion of low boiling paraffin hydrocarbons, and particularly normal paraffin hydrocarbons, to liquid motor fuels of high antiknock value without substantial loss of raw material.

This invention may be better understood by reference to the accompanying drawing wherein one specific embodiment exemplifying the invention is schematically shown in the figure. While the invention will be explained in connection with this figure by reference to the utilization of butane, which may be normal or isobutane, or a mixture thereof, for the manufacture of high antiknock motor fuel hydrocarbons, it is to be clearly understood that normal pentane, isopen-

tane or propane, or mixtures of any two or more of these light paraffins may be treated in a substantially similar manner to produce high antiknock motor fuels therefrom. As pointed out above, a convenient source of these materials is to be found in the C₃, C₄ or C₅ cuts from cracking still operation or in the overhead from a natural gasoline stabilizer or an appropriate fraction thereof. While the process will preferably be applied to fractions consisting largely of hydrocarbons containing the same number of carbon atoms, such separation is not absolutely necessary.

In this specific example butane may be introduced through line 1 to the dehydrogenation plant 2. In this plant butane may be dehydrogenated in any known manner, such as, for example, with the use of catalysts such as chromic oxide, magnesium oxide or zinc oxide supported on activated alumina, usually at relatively low pressures and temperatures of 900° to 1400° F., preferable 1000° to 1200° F. Hydrogen removed from the butane in the dehydrogenation plant 2 may be withdrawn through line 3 or passed through line 5 for further use, as explained below. This hydrogen will, of course, be separated from the mixture of butane and butene leaving the dehydrogenator by any well-known means, such as by distillation or absorption. The butene formed in the dehydrogenation plant 2 and unreacted butane may be withdrawn through line 4 and the mixture passed to a polymerization plant 8. In this plant butene is polymerized in any known manner, such as by means of phosphoric acid catalysts at temperatures between about 50° and 450° F. or sulfuric acid at temperatures up to about 200° F., to produce low boiling polymers. These polymers thus obtained are useful as motor fuel, but in order to form high antiknock aviation motor fuels therefrom, it is preferred to hydrogenate them, and for this purpose they are passed through line 9 to a hydrogenation plant 11, where the polymers are hydrogenated in any well-known manner as by means of a nickel catalyst under moderate hydrogen pressure or a molybdenum sulfide catalyst at higher pressures. Required hydrogen may be supplied to the hydrogenation zone from an outside source through line 6, or preferably may be supplied from the dehydrogenation plant 2 through lines 3 and 5. Hydrogenated polymers may be withdrawn from the hydrogenation plant 11 through a line 7.

As pointed out above, it is not found practicable in the commercial operation of polymerization processes to convert all the butene to polymers and for this reason the hydrocarbons leaving the polymerization plant 8 through line 10 will always contain some unpolymerized butene as well as the butane which remained undehydrogenated in plant 2. Under certain conditions it may be desirable to operate the polymerization plant so as to leave more than the minimum possible amount of butenes unpolymerized. For instance, the ratio of normal to isobutane in a C₄ cut is frequently of the order of two to one and it may then be desirable to polymerize only about 50% of the butene in order to leave sufficient to alkylate all of the isobutane available. It may also be desirable to limit the polymerization of butenes to about 50% since the polymers so produced have been found to contain a higher proportion of material boiling in the aviation fuel range and having a higher antiknock value, when hydrogenated, than when higher degrees of polymerization are employed. In any case, the mixture of unreacted butane and unpolymerized butene is then passed

through line 16 to an alkylation plant where the unpolymerized butene is used to alkylate isoparaffin to form high antiknock motor fuel hydrocarbons and is thus separated from the unreacted butane.

Thus, through line 16 the butane and unpolymerized butene from the polymerization plant 8 are led to an alkylation plant, where they may be introduced into the mixing zone 12 thereof. Isobutane to be alkylated and an alkylation catalyst, such as sulfuric acid, are also introduced to the mixing zone 12, and the three reactants are thoroughly mixed and agitated to promote the alkylation of the isobutane by the olefin. Additional, or all, the isobutane to be alkylated may be introduced to the mixing zone 12 through line 13, and the catalyst may be introduced through line 14. The reaction mixture from mixer 12 is discharged through line 15 into a separating zone 16 where the catalyst separates from the hydrocarbons. Separated catalyst, indicated by 16a, may be withdrawn through line 17 or returned through line 18 by pump 19 to the mixing zone 12. Fresh catalyst may be added through line 20 as needed.

From the upper part of separating zone 16 the hydrocarbon reaction mix consisting of normal paraffin, unreacted isoparaffin and alkymer product may be withdrawn through line 21 and passed to alkymer stabilizer 22, wherein the light hydrocarbons, such as normal butane and isobutane, are removed from the alkymer product. The alkymer product may be withdrawn through line 23 and the desirable components thereof used to make motor fuel. The mixture of normal butane and isobutane taken overhead from stabilizer 22 through line 24, may be condensed in condenser 25 and passed to receiver 26. From receiver 26 a portion of the condensed mixture of normal and isobutane may be returned to the stabilizer 22, while the remainder is passed through line 27 to a butane still 28 wherein isobutane is taken off overhead and the normal butane is withdrawn from the bottom.

The isobutane passing overhead from still 28 may be condensed in condenser 29, collected in receiver 30 and returned to the alkylation zone 12 through lines 32 and 13. The normal butane, now free of olefin, is withdrawn from the bottom of still 28 and returned to the dehydrogenation zone 2 through line 35. The mixture of isobutane and normal butane, or a portion of it, taken off overhead from stabilizer 22, which is also now free of olefins, may be returned directly to the dehydrogenation zone 2 through line 34, without separation in still 28, if desired, depending, of course, to a large extent upon the availability of isobutane and consequently on whether or not it must be conserved for alkylation.

In the alkylation mixing zone 12 it is desirable to have a high ratio of isoparaffin to olefin in order that the best alkymer product may be produced in good yield. For desirable operation this ratio should be at least above a molecular ratio of about ten to one and for the best results the molecular ratio should be as high as about fifty to one or above. In order to obtain this desired high ratio of isoparaffin to olefin in the mixing zone 12, isobutane may be added to the alkylation zone from an outside source through line 36, isobutane may be recycled from still 28 through line 32, or hydrocarbons from the upper part of separating zone 16, containing a substantial quantity of unreacted isobutane, may be returned through line 38 by pump 39 to the mixing zone 12, or any

combination of these three methods may be used.

In the operation of the process of the present invention it is found that the conversion of butane to butene in dehydrogenation plant 2 is usually about 25% to 30% per pass, and the polymerization of the butene in polymerization plant 8 may be from about 50 to 90%, as explained above, while the utilization of butene in the alkylation reaction is substantially complete, the overhead from still 22 seldom containing more than 0.1% olefin. It will thus be seen that by the foregoing process butane may be converted almost quantitatively to light liquid motor fuel of high antiknock value with a considerable saving in raw material, over an operation involving only dehydrogenation and polymerization, and a worthwhile improvement in the cycle of the dehydrogenation catalyst.

Although this invention contemplates any method of polymerization in polymerization plant 8 which produces polymers especially suitable, when hydrogenated, as high antiknock motor fuel components, it is found that best over-all results are obtained when the polymerization is sufficiently selective to remove all of the isobutene that may be present, since the alkymers produced by alkylating isobutane with the normal butenes instead of isobutene, are of better quality, especially insofar as antiknock value is concerned, and usually contain a higher proportion of the lighter components most desirable in aviation motor fuels. This selective removal of isobutene in plant 8 may be effected in any known manner as, for example, by a polymerization process in which isobutene may be in part selectively polymerized and in part copolymerized with normal butene by means of a phosphoric acid catalyst at temperatures between about 50° and 300° F. Either the so-called "solid phosphoric acid" catalyst prepared by calcining a mixture of phosphoric acid and diatomaceous earth or the "film type" catalyst consisting of a thin film of liquid phosphoric acid absorbed on a nonporous inert solid support, such as broken quartz, is suitable for this purpose. The selective removal of isobutene may also be effected by polymerizing the isobutene to di-isobutene by either of the above types of phosphoric acid catalyst, maintaining the reaction temperature between about 50° and 150° F., or by liquid sulfuric acid of about 60% to 70% H_2SO_4 at a temperature between about 90° and 130° F.

The catalyst for effecting the alkylation reaction may be any catalyst known to be useful for this purpose; however, sulfuric acid of concentration from about 95% to about 98% H_2SO_4 at temperatures ranging from the melting point of the catalyst when in use to about 150° F. is preferred. Other alkylation catalysts, such as chlorosulfonic acid, a mixture of chlorosulfonic acid and sulfuric acid, or a mixture of sulfuric acid and phosphoric acid may also be used. Such catalysts are referred to as catalysts of the sulfuric acid type. When the olefin is propylene, slightly higher temperatures may be desirable for the alkylation reaction. In order that the catalyst in the alkylation zone be maintained at a strength or an effectiveness which will produce a satisfactory alkymer product, some spent catalyst may be withdrawn through line 17 and a corresponding amount of fresh catalyst supplied through line 20.

Having now described and illustrated the process of our invention for the substantially complete conversion of normally gaseous paraffins to

liquid motor fuels of high antiknock value, we claim:

Process of manufacturing high antiknock motor fuel hydrocarbons from a mixture of low boiling hydrocarbons containing normal paraffins having more than two and less than six carbon atoms per molecule, which comprises subjecting such paraffins to a dehydrogenation stage in which said paraffins are partially dehydrogenated forming olefins, subjecting the resulting mixture of paraffins and olefins to a polymerization stage wherein the olefins are partially polymerized, separating the resulting polymers from the remaining mixture of said paraffins and said olefins,

subjecting said last-mentioned mixture to an alkylation stage in the presence of isoparaffin which is alkylated by said olefins thus freeing said mixture of substantially all of said olefins so that said paraffins contain less than about 0.1% olefin, separating normal paraffins therefrom and returning the normal paraffins thus separated to said dehydrogenation stage wherein said paraffins are further subjected to dehydrogenation, and returning separated isoparaffin to said alkylation stage.
